UNITED STATES PATENT OFFICE.

PETER HANSEN, OF COPENHAGEN, DENMARK.

DIVER'S HELMET.

No. 867,719.

Specification of Letters Patent.

Patented Oct. 8, 1907.

Application filed July 27, 1907. Serial No. 385,870.

To all whom it may concern:

Be it known that I, PETER HANSEN, a citizen of the Kingdom of Denmark, and a resident of Copenhagen, Denmark, Toldbodgade 11, diver, have invented new and useful Improvements in Divers' Helmets, of which the following is a specification.

The invention applies to a diver's helmet, which is lighter and quicker to buckle on than those hitherto known.

10 The invention is shown on the drawing, where Figure 1 shows the helmet in side view; Fig. 2 shows the same in front view; Fig. 3 the ring.

The diver's helmet or hat has the usual form and is as generally known fitted with glass panes as also with a cock and an airhole. The hat has hitherto been fixed on by placing the collar of the diver's dress on the top of the edge of the helmet, whereupon again on the top of the collar, iron bands were placed, which were held in place by nuts, screwed on bolts at the edge of 20 the helmet. This arrangement is defective thereby, that the iron bands must needs be parted in two or more pieces, inasmuch as an iron band of one piece will not be placeable down over the helmet, and as each such iron band according to its size must be fas-

tened by means of two or more nuts, it is rather time-wasting work to put the hat on and off, particularly so, if at the same time crests on the dress are to be placed into grooves on the iron bands. As contradistinguished therefrom, the plan of the present invention is to provide the hat with two holes corresponding to bolts *a* 25 on a ring *b*, which, before the helmet be put on, is placed below the collar *c*, the latter having a thickened edge. As the ring *b* is in one piece (continuous), it is sufficient to have two bolts, so that by this means a very considerable saving of time is effected, while at 30 the same time a completely reliable tightening is secured.

What I claim, and desire to secure by Letters Patent is:

A diver's helmet, characterized by a loose ring with two 40 screw bolts said ring being placed under the collar of the diver's dress and screwed on to the hat.

Signed by me at Copenhagen, Denmark this 15th day of July 1907.

PETER HANSEN.
